METHOD OF AND APPARATUS FOR RADIATING SOUND WAVES.

Application filed April 17, 1925. Serial No. 23,917.

Our invention relates to a method of and an apparatus for radiating sound waves, and is adapted particularly for use with radio-phone receiving systems, although capable of 5 more general application and not limited to such use.

It is well known that electromagnetically-operated sound-radiating devices commonly known as "loud speakers" that employ 10 diaphragms, sound chambers and horns are subject to certain limitations chief of which is their inability to reproduce the sounds initiated at the transmitting station without change of pitch and timbre or quality, the 15 main cause of such distortion being the impossibility of eliminating the natural period of the diaphragm and the stationary parts associated therewith. Another limitation to which such devices are subject is the absorption 20 of energy by the stationary parts associated with the diaphragm or other vibrating member and the resulting creation of mechanical vibrations in such parts with the result that, for a given amount of received 25 energy, the amplitude of the sound waves emitted is reduced.

While loud speakers employing sound radiating members such as plates and cones constructed and arranged to propagate relatively-intense sound waves through the air are in certain respects more satisfactory than those of the diaphragm and horn type and reproduce sounds more faithfully over a somewhat wider range of frequencies, they 35 do not, so far as we are advised, overcome such objections as the undue amplification of sound waves having a pitch approximately equal to the natural period of the vibrating system, the wasting of energy by the creation 40 of vibrations in parts intended to be stationary, and the inability to reproduce notes of the lower frequencies unless the area of the radiating member is prohibitively large.

The principal object of our invention, generally speaking, is to provide a method of and an apparatus for the radiation of sound waves of a wider range of frequencies than has heretofore been found possible without unduly increasing the linear dimensions of 45 the sound-radiating member or members, the greatest linear dimension of our device being only about one-thirty-seventh of the wave length in air of the lowest tone to be reproduced, and for the more faithful and

efficient reproduction of the quality and 55 pitch of the original sounds than can be effected by the prior methods and apparatus.

A special object of our invention is to provide a sound-radiating device in which the entire vibrating system is balanced, the force 60 acting on any element of the system being balanced by an equal and opposite force on the counterpart of such element, thereby eliminating the tendency of the moving elements to set up vibrations in the stationary parts associated therewith and making it possible to convert practically all of the available energy into sound waves.

A further object of our invention is to provide a sound-radiating device in which 70 for the lower audible frequencies a maximum change in the length of the gap between two oppositely-directed armatures is effected for a given change in the amplitude 75 of the variable component of the variable electric currents which energize the magnetizing coil whereby the mechanical period of the vibrating system is kept below the limit of audibility and distortion is eliminated.

Another object of our invention is to provide a sound-radiating device by means of which the sound waves produced by the two surfaces of a sound-radiating member constructed and arranged for the propagation 85 of relatively intense sound waves through the air will be prevented from interfering; or a sound-radiating device having two such sound-radiating members disposed oppositely by means of which the sound waves produced by the inner surfaces of said members 90 are prevented from interfering with those produced by the outer surfaces thereof.

Another object of our invention is to provide a sound-radiating device in which the sound-radiating member is actuated by one of two oppositely-directed armatures each carried by a flexible supporting member together with means for preventing interference between the sound waves produced by 100 the two surfaces of said member; or a sound-radiating device in which two oppositely-disposed sound-radiating members are employed, each actuated by one of said armatures, together with means for preventing 105 interference between the sound waves produced by the inner and outer surfaces of said radiating members.

A further object of our invention is to provide a sound-radiating device in which the sound-radiating member is supported at its center on its actuating armature; or in which 5 a conical sound-radiating member is supported at its apex on its actuating armature and, preferably, flares outwardly therefrom; or in which two such members oppositely disposed may be employed; such sound-radiating member preferably being supported solely by its actuating armature.

Another object of our invention is to provide a magnetic circuit in which there shall be a maximum change in the gap flux for a 15 given change in gap reluctance in order that the back electromotive force in the energizing winding will be a maximum for any motion of the armatures; and this object more specifically stated is to provide a magnetic 20 circuit formed in part by a permanent magnet having two oppositely-disposed and substantially rigid arms each supporting a flexible permeable member, such as a relatively-stiff disc, and two oppositely-directed armatures each carried by one of said discs and having their juxtaposed faces separated by a relatively-short air gap, the said circuit being so arranged that the reluctance of the path through the energizing coil is substantially equal to the reluctance of the path 25 between the poles of said permanent magnet which does not link said coil.

A further object of our invention is to provide means for adjusting and varying the 30 reluctance of the path through the energizing coil, or means for adjusting and varying the reluctance of the path between the poles of the permanent magnet, or both, for the purpose of securing a substantial equality 35 between the said reluctances.

Various other objects of our invention will hereinafter appear in the detailed description of the several illustrative embodiments 40 of our invention.

With the foregoing objects in view our invention in its broadest aspect comprises a method of converting variable electric currents into radiated sound waves, as distinguished from sound waves produced in a 45 casing or tube adapted to be held to the ear, which consists in superimposing the magnetic flux created by electric currents modified in accordance with the sound waves initiated at another point upon a constant magnetic flux, such as the flux created by a permanent magnet or the sum of such flux and the 50 flux created by the direct current component of such variable currents without altering the intensity of such constant magnetic flux, 55 then converting the resultant flux into equal and opposite mechanical motions, thereby eliminating the creation of vibrations in the stationary parts of the apparatus and effecting a saving in energy which for low 60 frequencies is quite noticeable, and finally 65

converting one of said mechanical motions into radiating sound waves; or else converting said mechanical motions into two sets of substantially-hemispherically-radiating sound waves of like pressure phase.

Our invention comprises also an apparatus for converting variable electric currents into radiated sound waves by subjecting a tympanum to a magnetic force and to a mechanical force which for a given position of said tympanum is equal and opposite to said magnetic force, and maintaining such substantial equality for all positions of said tympanum on either side of said given position throughout the working range thereof, 70 whereby for the lower audible frequencies a maximum vibrational amplitude of said tympanum is effected for a given change in said variable flux and the mechanical period of the vibrating system is kept below 75 the limit of audibility so that, as above set forth, the original sounds will be reproduced without substantial change in timbre or pitch.

In carrying out the foregoing methods our invention contemplates the use of two oppositely-disposed armatures supported, respectively, by substantially-parallel flexible members, such as relatively-stiff discs, means for magnetizing said armatures by variable 80 electric currents and a sound-radiating member constructed and arranged for the propagation of relatively intense sound waves through the air, as distinguished from a telephone diaphragm or the like, such 85 sound-radiating member, which may be plane, conical or of any suitable configuration, being supported at its center or at its apex, as the case may be, on one of said armatures, together with means for preventing 90 interference between the sound waves produced by the inner and outer surfaces of said radiating member. It contemplates also such use of two oppositely-disposed 95 sound-radiating members of any appropriate shape, conical or otherwise, each supported at its center on one of the armatures aforesaid, and in the case of conical radiating members, each cone preferably flares 100 outwardly from its point of support. In 105 either case we prefer to support the sound-radiating member solely by its actuating armature.

Our invention comprises means whereby the sound waves produced by the two surfaces of a sound-radiating member constructed and arranged for the propagation of relatively intense sound waves through the air will be prevented from interfering, or means whereby the sound waves produced by the inner surfaces of two such sound-radiating members oppositely disposed are prevented from interfering with the sound waves produced by the outer surfaces thereof, such means consisting in general of an 110 115 120 125 130

enclosure screening the space between the two surfaces of a single sound-radiating member or the space between the two sets of surfaces where two oppositely-disposed members are employed.

Our invention comprises also a sound-radiating device having two oppositely disposed sound-radiating members constructed and arranged for the propagation through 10 the air of relatively intense sound waves of like pressure phase together with means of any suitable character for preventing interference between the waves produced by the inner and outer surfaces of said members 15 whereby we obtain a reinforcing effect and a hemispherical, rather than spherical, sound wave distribution resulting in the doubling of the radiation resistance for each side which permits the halving of the area of 20 each radiating member without reducing the radiation resistance.

Our invention further comprises the provision of a magnetic circuit consisting in part of two oppositely-directed armatures, 25 the juxtaposed faces of which are separated by a relatively short gap and a permanent magnet having two oppositely-disposed and substantially-rigid arms each carrying a flexible permeable member by which said 30 armatures, respectively, are supported, the reluctance of the path through the armature-magnetizing winding being substantially equal to the reluctance between the poles of said magnet which does not link 35 said winding, whereby a maximum change in the gap flux is obtained for a given change in gap reluctance, this resulting in a maximum back electromotive force in said winding for any motion of the armatures; 40 and it comprises also means for adjusting and equalizing the reluctance of either or both of said paths.

Our invention comprises various parts and combinations of parts hereinafter more 45 fully described and set forth in the appended claims.

In the drawings which accompany and form a part of this specification we have shown in detail various embodiments of our 50 invention which have given good results in practice and also several modifications thereof; but these constructions are to be considered as illustrative rather than restrictive, because the principle underlying our invention 55 may be embodied in a variety of apparatus while the methods hereinbefore referred to are broader than mere apparatus and may be realized in practice by a variety of mechanical and electrical expedients.

Fig. 16 is a plan view of a perforated armature-supporting diaphragm;

Fig. 17 is a section taken on the line 17—17 of Fig. 16;

Fig. 18 is a plan view of a modification in 105 which a spider is employed for supporting the armatures;

Fig. 19 is a section taken on the line 19—19 of Fig. 18;

Fig. 20 is a horizontal section of a sound-radiating device in which only one radiating member is employed;

Fig. 21 is a longitudinal central section of a cone by means of which there are radiating sound waves having wave fronts that are initially plane;

Fig. 22 is a longitudinal central section of a cone by means of which there are radiated sound waves having wave fronts that are initially curvilinear.

Fig. 23 shows a set of curves drawn to rectangular co-ordinates and used in explaining the operation of our invention.

In the particular drawings selected for more fully disclosing the principle of our 125 invention 25 represents a permanent magnet having two oppositely-disposed substantially-rigid arms shown in the present instance as bolted to a block 26 of magnetic material which in turn is bolted to the base

of the casing 27, although it will be understood of course that we may employ a one-piece permanent magnet of the U- or horse-shoe shape, or of any other suitable shape. Secured to the inner sides of said arms near the upper ends thereof are two oppositely-disposed and substantially-parallel flexible permeable armature-supporting members 28, 28 which in that embodiment of our invention shown in Figs. 1 to 7, inclusive, are relatively stiff flexible discs each clamped between a pair of permeable rings 29, 29, arranged on the opposite faces of each disc near the periphery thereof, by screws or bolts 30. In the present instance the discs are secured to the permanent magnet by bolts 31 which assist in clamping the discs between their respective supporting rings.

The bolt 32 of non-permeable metal and the nuts 33 threaded thereon serve not only to clamp the discs between the rings 29, but also to hold said discs rigidly spaced apart at the portion of their circumferences farthest away from their points of attachment to the permanent magnet.

Two oppositely-directed armatures 34 herein shown as tubular are supported on said discs respectively at the centers thereof, and in the present instance each armature is shown as having a threaded end projecting through its supporting disc on which ends nuts 35 are threaded to clamp the disc between said nut and a shoulder 36 on the armature. It will be understood of course that any suitable means may be employed for securing said armatures to the discs.

Supported by the armatures in any suitable manner are oppositely-disposed sound-radiating members 37, 38 which may be of parchment, fibre or any other suitable material, and preferably the said sound-radiating members if conical as shown have their peripheral portions slightly bent back as shown at 39. It will be understood of course that the said sound-radiating members, each of which is supported at its center on one of said armatures, are not necessarily conical. In the present instance each conical tympanum or sound-radiating member is supported solely at its apex on its actuating armature by means of a sleeve 40 which passes through the apex and is threaded to the outwardly projecting end of the armature, said sleeve being formed integral with a conical portion 41 to which the tympanum may be attached by gluing or otherwise. The said sleeve and conical member 41 or whatever other device is employed for coupling the tympanum to the armature should be of wood, aluminum or other light material.

A magnetizing coil 42 is arranged in the space between the discs and is concentric with the armatures, said coil being wound on an insulating spool 43 supported in the

present instance in the rabbeted inner peripheries of the adjacent rings 29. In order to avoid the possible detrimental effects of air compression in the space between the spool and the discs, the inner rings 29 may be provided with a series of holes 44.

The juxtaposed faces of the armatures which are separated by a relatively short gap are plane and are normal to the common axis of the two armatures so that they are in absolute parallelism, and in our preferred construction the said armatures are slotted longitudinally to eliminate eddy current losses as shown at 45.

When the magnetizing coil 42 is energized by currents modified in accordance with sound waves initiated at another point as for example the variable undirectional currents in the plate circuit of a radiophone receiving system to which said coil may be electrically connected by the leads 46, or by variable electric currents of any nature, the constant magnetic flux in the air gap between the armatures created by the permanent magnet will be modified and hence the magnetic pull on the armatures will be changed, and as the same force acts on each armature in opposite directions, the motions of said armatures will be equal and opposite, thereby causing the outer surfaces of the cones to produce sound waves of like pressure phase and the inner surfaces thereof to produce sound waves of like pressure phase opposite to that of the phase of the sounds produced by said outer surfaces. It will be noted that a force acting on any element of the system is balanced by an equal and opposite force on the counterpart of such element so that the tendency of the moving elements to create mechanical vibrations in their associated stationary parts is eliminated and practically all of the energy of motion is converted into sound waves. This saving of energy is especially important in the reproduction of the lower frequencies and we have succeeded by our invention in reproducing the lowest audible notes with substantially the same facility as those of the upper register by using sound-radiating cones whose diameter is about twelve inches or approximately one thirty-seventh of the wave length in air of the sound made by the lower notes of a piano, say, about thirty cycles per second.

In order to reproduce sounds of low pitch the radiating member must have a comparatively large area because the radiation depends on the square of the area or on the fourth power of the radius if the tympanum is circular, when the radius of the surface is small with respect to the wave length of the sound, provided however that the sound waves produced by the opposite surfaces of the sound-radiating member are prevented from interfering with each other. In the absence of such means for preventing inter-

ference practically no radiation can be effected unless the radius is approximately a quarter wave length of the sound, and in the present instance our sound-radiating members would have to be about 220" in diameter in order to radiate waves having a frequency of thirty per second unless such interference was prevented.

We therefore provide means for preventing interference between the sound waves produced by the inner and outer surfaces of the cones 37, 38, or in the case where a single cone or sound-radiating member of other shape is employed as illustrated in Fig. 20, means for preventing interference between the sound waves produced by the inner and outer surfaces of the single sound-radiating member. Such prevention of interference may be accomplished in a variety of ways, and in the present instance we have illustrated the arrangement which we prefer to use for this purpose, viz, a casing 27 which sufficiently encloses and screens the space between the inner surfaces of said members to prevent the sound waves produced by said inner surfaces from interfering with the sound waves produced by the outer surfaces thereof. Inasmuch as the outer surfaces of the cones create sound waves of like pressure phase and interference between said waves and those produced by the inner surfaces is prevented, we obtain substantially the same reinforcing effect as if a rigid medial plane through which sound waves could not pass were placed between the cones normal to the axis of the armatures, and also a hemispherical, rather than a spherical, sound-wave distribution which results in the doubling of the radiation resistance for each side,—in other words, the area of each surface may be halved without reducing the radiation resistance.

The electromagnetic mechanism employed to vibrate a radiating surface must operate effectively with less amplitude and with larger force than the mechanism employed to actuate the diaphragm of a loud speaker of the horn type, and therefore some form of lever is usually employed to couple a radiating surface to its actuating mechanism. We have found, however, that such lever connection is unnecessary in our improved sound-radiating device, for we obtain by electromagnetic means the virtual equivalent of a mechanical lever increasing the actuating force on the radiating surface. We thereby eliminate unnecessary weight in the moving parts because the smaller radiators which we are able to use may be made of lighter material than those of larger size heretofore found necessary, there is no weight required for mechanical levers and as the armatures have the same amplitude as the radiating members, the effect of their weight is not increased as it would be if mechanical levers were necessary. It is well understood of course that for reproduction of sound waves of the higher frequencies the vibrating members must be as light as feasible, and therefore it will be seen that the elimination of unnecessary weight rendered possible as aforesaid is an important feature of our invention. It will be noted in this connection that by employing two armatures separated by a single gap the relative travel of the moving parts is doubled and the weight thereof is reduced.

It will of course readily occur to those skilled in the art that a further reduction in the weight of the moving parts may be effected by shortening the armatures and introducing a fixed core in the gap between their proximate faces, but this arrangement has certain disadvantages, viz, there are two gaps to maintain in close adjustment, there is an increased magnetic leakage, and the magnetomotive force at the gaps is reduced because obviously neither gap can be at the center of the coil; and while we consider this arrangement within the scope of our invention, we nevertheless prefer to use two armatures separated by a single gap and to obtain any desirable further reduction in weight by shortening the armatures and employing a narrower or flatter coil.

One of the most important features of our invention, the maintaining of the mechanical period of the vibrating system below the limit of audibility so that the original sounds will be reproduced without substantial change in quality or pitch, is accomplished in the following manner: The discs 28, 28, are so designed as to size, stiffness, elasticity and mode of support that for a given length of gap between the armatures, say 0.005" or for a given position of the tympanum, the force exerted on said armatures by the resultant of the flux of the permanent magnet and the flux created by the direct current component of the variable currents energizing the coil is equal and opposite to the mechanical force exerted thereon by said discs, and substantially such equality is maintained throughout the working range of the apparatus, that is, for gaps slightly longer and gaps slightly shorter than said given gap and consequently for all positions of the tympanum on either side of said given position, whereby for the lower audible frequencies a maximum change in the length of said gap and a maximum vibrational amplitude of said tympanum is effected for a given change in the amplitude of the variable component of said variable electric currents or for a given change in said magnetic flux. When the several parts are constructed and arranged in the manner aforesaid we have found that sounds are reproduced without distortion and that notes of the lowest audible frequency which are

absent in the reproduction effected by the loud speakers of the prior art are emitted with the same fidelity as those of the upper register.

The equilibrium above mentioned may be demonstrated by de-energizing the winding 42 and adjusting the screw 47 the function of which is hereinafter more fully described until the gap between the armatures 10 is as short as the normally-unflexed discs and the normal positions of the arms of the permanent magnet will permit, and then energizing said coil by direct current having a value of the order of that of the current 15 flowing in the plate circuit of the usual radiophone receiving system. The vibrating system will then immediately spring into a position of equilibrium, the armatures moving in opposite directions against the retractile force of the discs and reducing the 20 length of the gap. It will then be found that a very slight pressure exerted by the fingers on the discs will suffice to close the gap, but if the winding is de-energized by 25 disconnecting the same from the plate circuit it will be difficult to exert sufficient pressure with the fingers on the discs to overcome the retractile force thereof and appreciably alter the gap length.

The foregoing will be made clearer by 30 reference to the diagram shown in Fig. 23 in which the curve *a* represents the variation with gap length of the normal magnetic force tending to close the same and the curve 35 *b* represents the variation with gap length of the retractile force of the discs which tends to open the same. It will be noted that for a gap length of 0.005", in this particular example, the ordinates of the curves 40 *a* and *b* are equal and opposite which means of course that the vibrating system is in equilibrium. The curve *c* which represents the algebraic sum of the curves *a* and *b* crosses the zero axis at 0.005", of course, 45 and is negative for shorter gap lengths and positive for longer gap lengths. The normal magnetic force tending to close the gap is a function of the permanent magnetic flux and the flux created by the direct current component of the variable electric currents energizing the coil. When the radiophone receiving system is in operation and a uni-directional pulsatory current is created in the plate circuit thereof, the variable 50 component of such current flowing through the coil 42 increases the magnetic pull tending to close the gap, and in such case the dotted line curve *d* represents the variation of the total magnetic flux acting on the armatures while the dotted line curve *e* will then represent the effective pull on the armatures, that is to say, the difference between the 55 total magnetic pull tending to close the gap and the restoring mechanical force of the discs. In the case assumed the dotted line

curve *e* crosses the zero axis at 0.0025" and at that point the vibrating system is in equilibrium at the instant the ordinates of the curve *b* and *d* are equal and opposite. It will be understood of course that the curve *d* is constantly varying and that the point at which the curve *e* crosses the zero axis is changing continually, and careful consideration of Fig. 23 will show that the two opposing forces acting on the armature are substantially equal and opposite throughout the working range of the apparatus. 70

In order to increase the efficiency of our improved sound radiating device for use with high radiation damping, we prefer to 80 so arrange matters that the magnetic reluctance of the path through the energizing coil is substantially equal to the magnetic reluctance of the path between the poles of the permanent magnet which does not link said coil, and provide means for adjusting and varying the reluctance of either or both of said paths.

The total magnetic flux through the mid-point of a permanent magnet is not effected 90 by the reluctance of the path between its poles, changes in reluctance altering the distribution of the flux but not the amount. There are two paths for the flux, one through the armatures 34, 34, and air gap, this path 95 linking the winding 42, and the other comprises all leakage paths outside said winding, such as the paths between the two arms 25, 25, the outer portions of the disc 28, 28, the clamping rings 29, 29, etc., the flux dividing inversely as the reluctances of the two 100 paths.

The flux *f* through the gap is given by

$$f = F \left(\frac{1}{1 + \frac{R_g}{R_l}} \right) \quad 105$$

where R_g is the gap reluctance, R_l is the leakage reluctance and F is the total flux, 110 the equation containing only two variables f and R_g . In order that the back electromotive force in the winding 42 will be a maximum for any motion of the armatures 34, 34, we may determine values for F and R_l which make 115

$$\frac{df}{dR_g}$$

a maximum when f is as great as possible 120 without saturating the iron in the armatures.

The gap flux f is essentially a variable depending among other things on the gap reluctance which is a function of gap length and while the best value for f will have to 125 be determined empirically we have found that the limiting value thereof for good operation is such that will be just sufficient to saturate the armatures as much as is desirable when the gap is closed. 130

We have ascertained experimentally that the maximum effect occurs when the leakage reluctance is approximately equal to the average gap reluctance in which case f is equal to F . When this relation obtains a given change in magnetic flux produces a maximum pull on the armatures for a gap of given length.

In order to secure and maintain the substantial equality of the gap reluctance and the leakage reluctance as aforesaid, we provide a leakage path chiefly through the air, so as not to introduce iron losses, which has a reluctance approximately equal to that of the gap, and we provide also means for adjusting one or both of said reluctances. Preferably the permanent magnet has a flux about double that required to saturate the armatures, about one-half of said flux passing through the armatures and one-half passing outside the same, and the armature-supporting discs and the pole pieces of said permanent magnet preferably are comparatively large in order that the foregoing relation between the reluctances may obtain.

Although the relation between the gap reluctance and leakage reluctance is not critical, a departure as large as about twenty-five per cent on either side of equality not being fatal to good operation, we have found it desirable to adjust one or both of said reluctances when the device is in operation in order to get the best response.

One very simple means for adjusting said reluctances consists in the screw 47 threaded through one of the arms 25 of the permanent magnet and having its end bearing against the other arm whereby the poles of the magnet may be sprung and the armatures 34, 34, separated. The separation of said armatures will of course increase the reluctance of the air gap and to a slight and almost inappreciable degree the leakage reluctance also.

Another means for maintaining the aforesaid relation between the two reluctances is illustrated in Figs. 6 and 7 in which an iron segment 48 carried by the rod 49 threaded into the bushing 50 and terminating in the knurled head 51 may be inserted into and withdrawn from the space between the rings 29, 29, thereby to alter the leakage reluctance. By means of said iron segment a certain amount of the flux is shunted from the armature gap which results in lengthening said gap and hence increasing its reluctance, while at the same time the reluctance of the leakage path is reduced. It is to be understood however that we do not limit ourselves to either of the arrangements described for varying the reluctance of either of said paths inasmuch as a variety of equivalent means will readily occur to those skilled in the art.

Our sound-radiating device is operative 65 without the permanent magnet 25, 25, when the operating current is uni-directional as for example the current in the output circuit of a vacuum tube, and an embodiment of our invention which does not employ such permanent magnet is shown in Figs. 8 and 9 in which the rings 29, 29 are directly connected to each other by permeable members 52, 52, the device in such case being supported in the casing 27 by any suitable 75 means and its operation being substantially as above set forth in connection with Figs. 1 to 5 inclusive.

In Figs. 10 and 11 cantilever springs 53 attached to the poles of the permanent magnet 54 take the place of the discs 28, 28 as armature-supporting members, the winding 55 enclosing the armatures as above set forth in connection with the winding 42. In Fig. 12 we show an alternative means for magnetizing the armatures, a winding 56 in such case being disposed around one or both of the cantilever springs 53. We prefer however to employ windings of the type shown in the other figures in which the gap between the armatures is at the center of the coil.

Another modification is shown in Figs. 13, 14 and 15 in which the armatures 34, 34 are supported on the thin plate springs 57, 95 57 bolted at their ends to the transversely-extending pole pieces 58, 58, of the permanent magnet 25. In this construction the flanges 59 of the spool on which the coil 42 is wound are extended as shown and supported by the ends of the bolts 60 whereby the springs 57 are attached to the magnet pole pieces.

The modifications shown in Figs. 16 to 19 inclusive illustrate constructions by which the weight of the vibrating system may be reduced. In Figs. 16 and 17 the diaphragm 61 is perforated as shown at 62, 62. In Figs. 18 and 19 a four-armed spider 63 is employed for supporting each armature. In both cases and in constructions where other forms of armature-supporting members are used, the same considerations set forth above in connection with the detailed description of Figs. 1 to 5 inclusive apply.

We have found that it is not essential to employ two oppositely-disposed sound-radiating members and that good results are obtained by omitting one such member but retaining the vibrating system otherwise intact.

Fig. 20 shows a sound-radiating device embodying our invention that is particularly designed for incorporation in the cabinet of a radio-receiving set. In this construction the free armature is found to react on the armature which supports the sound-radiating member 37 and to reinforce its action.

The nut 35 whereby the free armature is clamped to one of the discs 28 may be slightly larger than the corresponding nut shown in Fig. 5 for securing the other armature to the other disc, if the latter nut be employed, or as shown in Fig. 20 the threaded sleeve 40 may serve to clamp the cone-supporting armature to its disc. In either case the weight of said nut on the free armature will serve in a certain degree to compensate for the reduction of weight resulting from the omission of the cone 38. There is evidently a magnetic coupling between the armatures which tends to balance the two sides of the vibrating system.

In the cone 64 shown in section in Fig. 21 the height is such that sound waves radiated therefrom will reach the plane of the base at the same time that such waves traveling through the material of the cone from the apex 65 reach the outer periphery 66 so that the wave front is initially plane, the dotted lines 67, 67 indicating the successive positions of the wave fronts of the radiated waves. The dotted lines 68, 68 indicate approximately the wave fronts of the waves radiated from the inner surface of the cone, and it will be obvious that there will be a greater radiation of energy from the outer than from the inner surface.

In Fig. 22 however the cone 69 is shallower than that shown in Fig. 21 so that by the time the waves have traveled from the apex 70 to the outer periphery 71 through the material of the cone itself, the radiated waves have passed beyond the cone base and the wave front initially is curvilinear as indicated by the dotted line 72. A sound-radiating device provided with a cone of the shape shown in Fig. 21 will have a pronounced directional effect while there will be substantially no directional effect if a cone of the type shown in Fig. 22 is used.

While not limiting ourselves to either type of cone or in fact to a sound-radiating member of any particular shape, we prefer to employ conical sound-radiating members capable of producing sound waves having wave fronts which are initially curvilinear.

In our improved sound-radiating device it is possible to adjust and maintain the gap between the armatures with extreme accuracy and the gap length can be made as short approximately as 0.001" when the energizing current is of small amplitude. It is therefore important in order to get the benefit of such fine adjustment that the length of the gap be uniform over the entire surface of the armature faces, this requiring that said faces be parallel as well as plane. In the present instance this result is accomplished by making each armature hollow and having its face normal to its axis and then assembling the vibrating system on a close-fitting mandrel and adjusting the several screws 30 whereby

the discs 28 are clamped between their rings 29 until the mandrel can be removed without effort, in which case the juxtaposed faces of the oppositely-directed armatures are necessarily accurately parallel.

While we have shown the discs 28 provided with a series of perforations 44, it is possible to use solid or unperforated diaphragms as supports and to close the bores of the outwardly-projecting threaded ends of the armatures as by screws or otherwise so as completely to enclose the space between the diaphragms and coil-supporting spool within which the armature gap is located, so that said gap will be in a dust-proof closure.

Having thus described illustrative embodiments of our invention and methods of obtaining the objects hereinbefore recited without however limiting ourselves thereto, what we claim and desire to secure by Letters Patent is:—

1. As an improvement in the art of converting variable electric currents into relatively intense radiated sound waves, the method herein described which consists in creating a variable magnetic flux by electric currents modified in accordance with sonorous vibrations, superimposing said variable magnetic flux upon a constant magnetic flux without altering the intensity of the latter, converting the resultant magnetic flux into two equal and opposite mechanical motions and converting said mechanical motions into two sets of substantially-hemispherically-radiating sound-waves of like pressure phase.

2. As an improvement in the art of converting variable electric currents into relatively intense radiated sound waves, the method herein described which consists in creating a variable magnetic flux by electric currents modified in accordance with sonorous vibrations, superimposing said variable magnetic flux upon a constant magnetic flux without altering the intensity of the latter, converting the resultant magnetic flux into two equal and opposite mechanical motions and converting one of said mechanical motions into substantially hemispherically radiating sound waves.

3. A sound-radiating device comprising in combination, two oppositely-disposed armatures, means for magnetizing said armatures by variable electric currents, a supporting member for each of said armatures, a sound-radiating member constructed and arranged for the propagation of relatively-intense sound waves through the air, said sound-radiating member being supported at its center on one of said armatures, and means for preventing interference between the sound waves produced by the two surfaces of said sound-radiating member.

4. A sound-radiating device comprising in combination, two oppositely-disposed armatures, means for magnetizing said armature

by variable electric currents, a supporting member for each of said armatures, a conical sound-radiating member constructed and arranged for the propagation of relatively-intense sound waves through the air, said sound-radiating member being supported at its apex on one of said armatures, and means for preventing interference between the sound waves produced by the two surfaces of said sound-radiating member.

5 5. A sound-radiating device comprising in combination, two oppositely-disposed armatures, means for magnetizing said armatures by variable electric currents, a flexible supporting member for each of said armatures, two oppositely-disposed sound-radiating members constructed and arranged for the propagation of relatively-intense sound waves through the air, each said sound-radiating member being supported at its center on one of said armatures; and means for preventing interference between the sound waves produced by the inner surfaces of said sound-radiating members and the sound waves produced by the outer surfaces thereof.

10 6. A sound-radiating device comprising in combination, two oppositely-disposed armatures, means for magnetizing said armatures by variable electric currents, a flexible supporting member for each of said armatures, two oppositely-disposed conical sound-radiating members constructed and arranged for the propagation of relatively-intense sound waves through the air, each said sound-radiating member being supported at its apex on one of said armatures, and means for preventing interference between the sound waves produced by the inner surfaces of said sound-radiating members and the sound waves produced by the outer surfaces thereof.

15 7. A sound-radiating device comprising in combination, two oppositely-disposed armatures, means for magnetizing said armatures by variable electric currents, a flexible supporting member for each of said armatures, a sound-radiating member constructed and arranged for the propagation of relatively-intense sound waves through the air, said sound-radiating member being supported solely at its center on one of the said armatures, and means for preventing interference between the sound waves produced by the two surfaces of said sound-radiating member.

20 8. A sound-radiating device comprising in combination, two oppositely-disposed armatures, means for magnetizing said armatures by variable electric currents, a flexible supporting member for each of said armatures, a conical sound-radiating member constructed and arranged for the propagation of relatively-intense sound waves through the air, said sound-radiating member being supported solely at its apex on one of said armatures, and means for preventing interference

between the sound waves produced by the two surfaces of said sound-radiating member.

25 9. A sound-radiating device comprising in combination, two oppositely-disposed armatures, means for magnetizing said armatures by variable electric currents, a flexible supporting member for each of said armatures, two oppositely-disposed sound-radiating members constructed and arranged for the propagation of relatively intense sound waves through the air, each said sound-radiating member being supported solely at its center on one of said armatures, and means for preventing interference between the sound waves produced by the inner surfaces of said sound-radiating members and the sound waves produced by the outer surfaces thereof.

30 10. A sound-radiating device comprising in combination, two oppositely-disposed armatures, means for magnetizing said armatures by variable electric currents, a flexible supporting member for each of said armatures, two oppositely-disposed conical sound-radiating members constructed and arranged for the propagation of relatively intense sound waves through the air, each said sound-radiating member being supported solely at its apex on one of said armatures, and means for preventing interference between the sound waves produced by the inner surfaces of said sound-radiating members and the sound waves produced by the outer surfaces thereof.

35 11. A sound-radiating device comprising in combination, two oppositely-disposed armatures, means for magnetizing said armatures by variable electric currents, a flexible supporting member for each of said armatures, a conical wave-radiating member constructed and arranged for the propagation of relatively-intense sound waves through the air, said sound-radiating member being supported at its apex on one of said armatures and flaring outwardly from its supporting armature, and means for preventing interference between the sound waves produced by the two surfaces of said sound-radiating member.

40 12. A sound-radiating device comprising in combination, two oppositely-disposed armatures, means for magnetizing said armatures by variable electric currents, a flexible supporting member for each of said armatures, a conical wave-radiating member constructed and arranged for the propagation of relatively-intense sound waves through the air, said sound-radiating member being supported solely at its apex on one of said armatures and flaring outwardly from its supporting armature, and means for preventing interference between the sound waves produced by the two surfaces of said sound-radiating member.

13. A sound-radiating device comprising in combination, two oppositely-disposed armatures, means for magnetizing said armatures by variable electric currents, a flexible supporting member for each of said armatures, two oppositely-disposed conical sound-radiating members constructed and arranged for the propagation of relatively intense sound waves through the air, each said sound-radiating member being supported at its apex on one of said armatures and flaring outwardly from its supporting armature, and means for preventing interference between the sound waves produced by the inner surfaces of said sound-radiating members and the sound waves produced by the outer surfaces thereof.

14. A sound-radiating device comprising in combination, two oppositely-disposed armatures, means for magnetizing said armatures by variable electric currents, a flexible supporting member for each of said armatures, two oppositely-disposed conical sound-radiating members constructed and arranged for the propagation of relatively intense sound waves through the air, each said sound-radiating member being supported solely at its apex on one of said armatures and flaring outwardly from its supporting armature, and means for preventing interference between the sound waves produced by the inner surfaces of said sound-radiating members and the sound waves produced by the outer surfaces thereof.

15. In a sound-radiating device, a permanent magnet having two oppositely-disposed substantially-rigid arms, two oppositely-disposed and substantially-parallel flexible permeable members, each attached to one of said arms, two oppositely-directed armatures carried by said members, respectively, the juxtaposed faces of said armatures being separated by a relatively-short gap, and means for magnetizing said armatures by variable electric currents.

16. In a sound-radiating device, a winding, a permanent magnet having two oppositely-disposed arms, and two oppositely-directed armatures supported thereby and arranged for magnetization by said winding, the juxtaposed faces of said armatures being separated by a relatively-short gap and the magnetic leakage path between the poles of said permanent magnet not linking said winding having a reluctance approximately equal to the reluctance of the path through said winding.

17. In a sound-radiating device, a winding, a permanent magnet having two oppositely-disposed arms, two oppositely-directed armatures supported thereby and arranged for magnetization by said winding, the juxtaposed faces of said armatures being separated by a relatively-short gap and the magnetic leakage path between the poles of said

permanent magnet not linking said winding having a reluctance approximately equal to the reluctance of the path through said winding, and means for varying the reluctance of one of said paths.

18. In a sound-radiating device, a winding, a permanent magnet having two oppositely-disposed arms, two oppositely-directed armatures supported thereby and arranged for magnetization by said winding, the juxtaposed faces of said armatures being separated by a relatively-short gap and the magnetic leakage path between the poles of said permanent magnet not linking said winding having a reluctance approximately equal to the reluctance of the path through said winding, and means for varying the separation of said armatures.

19. In a sound-radiating device, a permanent magnet having two oppositely-disposed arms, two oppositely-disposed and substantially-parallel flexible permeable members, each attached to one of said arms, two oppositely-directed armatures carried by said members, respectively, the juxtaposed faces of said armatures being separated by a relatively-short gap, and means for magnetizing said armatures by variable electric currents, the force exerted on said armatures by the resultant of the flux of said permanent magnet and the flux created by the direct current component of said variable electric currents for a given length of said gap being equal and opposite to the force exerted thereon by said members, and being substantially equal thereto, and opposite, throughout the working range of said device whereby for the lower audible frequencies a maximum change in the length of said gap is effected for a given change in the amplitude of the variable component of said variable electric currents.

20. In a sound-radiating device, two oppositely-disposed substantially-parallel rigidly-supported flexible members, two oppositely-directed hollow armatures carried by said members, respectively, the juxtaposed faces of said armatures being separated by a relatively-short gap, and means for magnetizing said armatures by variable electric currents.

21. In a sound-radiating device, two oppositely-disposed substantially-parallel rigidly-supported flexible members, two oppositely-directed longitudinally-slotted hollow armatures carried by said members, respectively, the juxtaposed faces of said armatures being separated by a relatively-short gap, and means for magnetizing said armatures by variable electric currents.

22. In a sound-radiating device, two oppositely-disposed substantially-parallel rigidly-supported flexible discs, two oppositely-directed armatures carried by said discs, respectively, the juxtaposed faces of said armatures being separated by a relatively-

short gap, and means disposed between said discs for magnetizing said armatures by variable electric currents.

23. In a sound-radiating device, two oppositely-disposed substantially-parallel rigidly-supported relatively-stiff flexible discs, two oppositely-directed armatures carried by said discs respectively, the juxtaposed faces of said armatures being separated by a relatively-short gap, and means disposed between said discs for magnetizing said armatures by variable electric currents.

24. In a sound-radiating device, two oppositely-disposed substantially-parallel flexible discs, two rings arranged, respectively, on the opposite faces of each disc near the periphery thereof, means for clamping each disc between one of the pairs of rings, means rigidly supporting each pair of rings, two oppositely-directed armatures carried by said discs, respectively, the juxtaposed faces of said armatures being separated by a relatively-short gap, and means disposed between said discs for magnetizing said armatures by variable electric currents.

25. In a sound-radiating device, two oppositely-disposed substantially-parallel rigidly-supported flexible members, two oppositely-directed armatures carried by said members, respectively, and having a common axis, the

juxtaposed faces of said armatures being plane and normal to said axis, and being separated by a relatively short gap, and means disposed between said discs for magnetizing said armatures by variable electric currents.

26. In a sound-radiating device two oppositely-disposed substantially-parallel flexible discs, means rigidly supporting each disc at or near its periphery, two oppositely-directed armatures carried by said discs, respectively, the juxtaposed faces of said armatures being separated by a relatively-short gap and means disposed between said discs for magnetizing said armatures by variable electric currents.

27. In a sound-radiating device two oppositely-disposed substantially-parallel rigidly-supported perforated flexible discs, two oppositely-directed armatures carried by said discs, respectively, the juxtaposed faces of said armatures being separated by a relatively-short gap and means disposed between said discs for magnetizing said armatures by variable electric currents.

In testimony whereof, we have hereunto subscribed our names this 16th day of April, 1925.

RICHARD D. FAY.
ROBERT E. BREWER.
